CONDUCTOR SUPPORT

Howard Albert Frey, Towson, and Robert Leslie McCoy, Baltimore, Md., assignors to Locke, Incorporated, Baltimore, Md., a corporation of Maryland

Application October 4, 1944; Serial No. 557,152

14 Claims. (Cl. 248—63)

1

Our invention relates to conductor supports and more particularly to conductor supports of the character used with post or pin type insulators. Its principal object is to provide a support which will enable the conductor clamp to be readily, easily and safely removed from its mounting under "hot line" conditions, that is, while current is still flowing through the conductor, without completely disassembling the conductor clamp.

A primary feature of the invention consists in providing a conductor clamp with oppositely projecting pintles which are pivotally supported in a mounting from which the clamp may be removed without being disassembled.

Another feature of the invention consists in providing a cotter pin for locking the conductor seat in pivotal association with the mounting, the pin having an offset portion normally preventing its removal from the mounting when moved to a position permitting the clamp to be removed from the mounting.

Another feature of the invention consists in arranging the keeper of the clamp which is pivotally and removably supported in a mounting so that the clamp may not be removed from the mounting when the keeper is in clamping relation with the conductor.

Other and more specific features of the invention, residing in advantageous forms, combinations and relations of parts, will hereinafter appear and be pointed out in the claims.

In the drawings,

Figure 1 is a plan view of the conductor support.

Figure 2 is a vertical sectional view taken on line 2—2 of Figure 1.

Figure 3 is an end view of the conductor support.

Figure 4 is a transverse sectional view taken on line 4—4 of Figure 1.

Figure 5 is a plan view of a conductor support embodying a different form of the invention.

Figure 6 is a view partly in section and partly in elevation of the conductor support illustrated in Figure 5.

Referring more particularly to the drawings, 1 indicates a pin type insulator having a recess 2 in its upper portion for receiving a downwardly extending flange or the like 3 of a mounting 4 which, as shown in Figure 4, is secured by cement 5 to the insulator 1. The mounting is formed with two upwardly extending oppositely arranged portions or ears 6 and 7 in which oppositely extending pintles 8 and 9 of a conductor clamp are respectively pivotally supported.

2

The pintles 8 and 9 are formed on a seat member 10 of the conductor clamp which also includes a keeper member 11. The pinte 8 of the seat member is pivotally supported within a recess formed in the inner face of the upstanding portion 6 of the mounting 4 while pinte 9 is pivotally supported in upstanding portion 7 between two laterally spaced portions 12 and 13, respectively.

With the pintles arranged as described, the seat 10 of the clamp may be only removed from mounting 4 by raising the side of the seat having pinte 9, disconnection of the seat from the mounting by axial movement of the seat being prevented by the end walls 14 of the upstanding portions 6 and 7 of the mounting.

To prevent upward movement of the side of the seat having the pinte 9, a cotter pin 15 is employed for holding or locking the pinte 9 in pivotal relationship with the mounting.

The cotter pin 15 has two laterally spaced arms or legs 16, one of which is crimped or otherwise formed with an offset portion 17 intermediate its ends which normally prevents the cotter from being moved to unlocking position, that is to say, a position in which the adjacent pinte 9 of the seat 10 may be moved upwardly to disconnect the clamp from the mounting 4. This crimped portion 17 of the cotter pin is so formed with respect to the eye or connecting end portion 18 of the cotter as to be in contiguous relation with the inner face of the portion 13 of the ear 7 and it is also formed in such manner that the legs or arms of the cotter must be compressed or forced together in order that it may pass through the aperture in the portion 13. Thus when the cotter is moved into locking position, the arms thereof will spring apart after the crimped portion 17 passes through the aperture in the portion 13 and the cotter will, therefore, be held in locking position against unintentional displacement.

Due to the danger of working around a highly charged conductor, it is desirable to prevent the cotter pin from being entirely removed from the mounting when it is moved into unlocking position to permit the clamp to be removed from the mounting. For this purpose, the outer end of the upper one of the arms of the cotter pin is formed with an offset portion 19 which, when the cotter has been withdrawn sufficiently from the mounting to permit removal of the conductor clamp, engages the inner face of the upper part 20 of the upstanding portion 13. As will be seen in Figure 1, the inner face of the upper part 20 is spaced outwardly from the inner face of the

remainder of the portion 13 so that the outer end of the lower arm of the cotter will not interfere with the pintle 9 when being raised to remove the clamp from the mounting. The outer end portion of the lower arm of the cotter inclines downwardly as shown in Figure 2 so that, upon rapid movement of the cotter into unlocking position, it will tend to force the outer end portion of the upper end of the cotter upwardly and thus insure engagement of the offset portion 19 with the upper part 20 of the portion 13 on the mounting.

One of the legs of the cotter pin is preferably maintained in yielding engagement with the adjacent pintle of the clamp seat so as to eliminate possible radio interference which might arise from the pintle vibrating because of vibrations transmitted thereto from the conductor. For this purpose, the upper wall 21 in the aperture in the portion 12 of the mounting is inclined downwardly so that, when the cotter pin is moved into locking position, its arms will be forced toward each other and the lower arm will thus be maintained in yielding engagement with the pintle.

The keeper 11 of the clamp is connected to the seat member 10 for clamping the conductor by a pair of bolts 22 which it will be seen need not be removed to disconnect the clamp from the mounting. The keeper is preferably formed on opposite faces with portions of different curvature so that merely by reversing or turning the keeper over, it can be used with conductors of widely different diameters.

In the modified form of the invention shown in Figures 5 and 6, both ears or lugs 23 of the mounting 24 for the conductor clamp are formed with apertures 25, instead of one of the lugs or ears having laterally spaced portions as in the form of the invention illustrated in Figures 1 to 4, inclusive. The seat member 26 of the conductor clamp shown in Figures 5 and 6 has oppositely projecting pintles 27 which extend into the apertures 25 of the lugs 23 and the keeper member 28 thereof is of such construction that, when it is secured to the seat member for clamping the conductor thereto, its outer ends are in such contiguous relation with the inner faces of the lugs 23 that the seat member 26 cannot be moved a sufficient distance axially of the pintles 27 to enable the clamp to be disconnected from the mounting.

To remove the clamp from the mounting, it is, however, merely necessary to loosen the bolts 29, which connect the seat and keeper members together, so that one end of the keeper may be raised sufficiently above the adjacent lug of the mounting to enable the clamp to be moved axially of the pintles 27 a distance sufficient to withdraw the pintle on the opposite side of the clamp from the aperture in the lug with which it is associated. The portion of the clamp adjoining the pintle which has been withdrawn from its lug is then raised above that lug so that the clamp can be moved axially of the pintles in the opposite direction to withdraw the other pintle from the other lug of the mounting.

The upper surface of the inner portion of each aperture is preferably inclined upwardly as indicated at 30 to facilitate the withdrawal of the pintle which is first removed from the mounting and the lower surface of the outer portion of each aperture is downwardly inclined as indicated at 31 to facilitate removal of the last pintle. By providing the apertures in the lugs with inclined surfaces of the character indicated, it is not nec-

essary to loosen the bolts 29 as much as would otherwise be required. The bolts themselves are, of course, sufficiently long so that the nuts 32 need not be removed from them to permit the keeper to assume a position enabling the seat to be removed from the mounting.

In each form of the invention, it will be perceived that the conductor clamp is formed with oppositely projecting pintles which are pivotally supported in a suitable mounting to enable the clamp to angle sufficiently so that undue strains will not be placed on either the conductor or its support as a result of forces to which the conductor is normally subjected.

Various modifications in details of the two embodiments of the invention here described and illustrated may, of course, be made without departing from the spirit and scope of the invention as defined in the appended claims.

15 20 What is claimed is:

1. A conductor support involving a mounting, a seat member having oppositely projecting portions pivotally supported in said mounting, a keeper member, means connecting the keeper member to the seat member for clamping said members to a conductor, and means for releasably maintaining the seat member in pivotal association with said mounting, said last-named means being movable to permit the seat member to be removed from the mounting without disconnecting the keeper member from the seat member.

2. A conductor support involving a mounting having oppositely arranged upstanding portions, a conductor clamp having a seat member and 35 a keeper member, said seat member having oppositely projecting pintles pivotally supported in said upstanding portions, means connecting said seat and keeper members for clamping them to a conductor, and means for releasably maintaining 40 the seat member in pivotal association with said mounting, said last-named means being movable to permit the seat member to be removed from the mounting without disconnecting the keeper member from the seat member.

3. A conductor support involving a mounting having upwardly extending oppositely arranged portions provided with recesses in their inner faces, a seat member having oppositely projecting pintles pivotally supported in said recesses, a 50 keeper member, bolts connecting said members for clamping them to a conductor, and means extending substantially at right angles to an adjacent pintle for releasably maintaining the seat member in pivotal association with said mounting whereby the seat member may be removed from the mounting without disconnecting said bolts from said keeper and seat members.

4. A conductor support involving a mounting, a seat member having oppositely projecting 60 pintles pivotally supported in said mounting, portions of said mounting serving to maintain said member against horizontal movement longitudinally of a conductor keeper means for clamping the conductor to the seat member, and a cotter pin carried by said mounting for locking the seat member in pivotal relation with the mounting, said cotter pin having a portion engageable with the mounting when it is moved to unlocking position for normally preventing removal of the cotter pin from the mounting.

5. A conductor support involving a mounting having oppositely arranged upstanding portions, a conductor clamp having a seat member and a keeper member, said seat member having oppositely projecting pintles pivotally supported in

said upstanding portions against movement longitudinally of a conductor, and a cotter pin mounted on one of said upstanding portions for locking the seat member in pivotal association with the mounting, said cotter pin having an offset portion at its outer end engageable with a portion of the mounting upon movement of the pin to unlocking position for normally preventing its removal from the mounting.

6. A conductor support involving a mounting having oppositely arranged upwardly extending ears, a conductor clamp having a seat member and a keeper member, said seat member having oppositely projecting pintles pivotally supported in said ears against movement longitudinally of a conductor, one of said ears having laterally spaced portions between which the adjacent pintle of the seat member is pivotally disposed, and a cotter pin adapted to bridge the upper portion of said laterally spaced portions for locking the seat member to the mounting, said cotter pin having an offset portion at its outer end adapted to engage one of said laterally spaced portions upon movement of the pin to unlocking position for normally preventing removal of the pin from the mounting.

7. A conductor support involving a mounting, a seat member having oppositely projecting pintles pivotally supported in said mounting, keeper means for clamping a conductor to the seat member, and a cotter pin carried by said mounting and cooperable with one of said pintles for locking the seat member in pivotal association with the mounting, said cotter pin having legs normally disposed in spaced relation, one of said legs being adapted to be maintained in yielding engagement with the adjacent pintle by said seat when the cotter pin is disposed in locking position.

8. A conductor support involving a mounting, a seat member having oppositely projecting pintles pivotally supported in said mounting, keeper means for clamping a conductor to the seat member, and a cotter pin carried by said mounting and engageable with one of said pintles for locking the seat member in pivotal relation with the mounting, said cotter pin having legs normally disposed in spaced relation, and means for forcing said legs toward each other as the cotter pin assumes locking position to cause one of said legs to be maintained in yielding engagement with the associated pintle by the seat member.

9. A conductor support involving a mounting having oppositely arranged pairs of upstanding portions, a conductor clamp having a seat member and a keeper member, said seat member having oppositely projecting pintles each of which is pivotally supported between a pair of said upstanding portions, bolt means spaced from said pintles for connecting said seat and keeper members said means also serving to clamp said seat and keeper to a conductor, and a cotter pin carried by one of said pairs of upstanding portions for locking the seat member in pivotal association with said mounting, said cotter pin being adapted to be moved to unlocking position to permit the said seat member to be removed from the mounting without disconnecting the keeper member from the seat member.

10. A conductor support involving a mounting, a seat member having oppositely projecting portions pivotally supported in said mounting, a

keeper member, means connecting the keeper member to the seat member for clamping said members to a conductor, said seat member being movable axially of the pintles to disconnect it from said mounting, said keeper when secured in clamping relation to the seat member preventing axial movement of the seat member sufficiently to prevent the seat member from becoming disconnected from said mounting.

11. A conductor support involving a mounting including spaced upstanding portions, a seat member having oppositely projecting pintles pivotally supported in said portions of said mounting, a keeper member, and means for connecting the keeper to the seat member for clamping a conductor to the seat, the upstanding portions of said mounting engaging said keeper when the latter is in clamping position to prevent the seat member from being disconnected from the mounting when clamping the conductor against the seat.

12. A conductor support involving a mounting having oppositely arranged upstanding portions, a conducting clamp having a seat member and a keeper member, said seat member having oppositely projecting pintles pivotally supported in said upstanding portions, and bolt means connecting said seat and keeper members for clamping them to a conductor, said keeper member being cooperable with said upstanding portions when held by said bolt means in clamping relation to the seat to prevent the seat from being removed from said mounting.

13. A conductor support involving a mounting having upwardly extending apertured lugs, a conductor clamp having a seat member and a keeper member, said seat member having oppositely projecting pintles pivotally supported in the openings of said lugs, and bolt means connecting said seat and keeper members for clamping them to a conductor, the outer ends of said keeper member being adapted to be disposed adjacent the inner faces of the lugs and being cooperable therewith when the keeper is in clamping relation to the conductor for preventing the seat member from being disconnected from the mounting.

14. A conductor support involving a mounting having oppositely arranged upstanding portions, a conductor clamp having a seat member and a keeper member, said seat member having oppositely projecting pintles pivotally supported in said upstanding portions and said keeper member when in clamping relation to a conductor serving to prevent removal of the seat member from the mounting, and bolt means connecting the keeper and seat members adapted when loosened to permit the keeper to assume a position enabling the seat member to be disconnected from the mounting without removing the bolt means from said seat and keeper.
